CLAIM

The ornamental design for an ovenware, as shown and described.

DESCRIPTION

1. Ovenware

1.1 : Perspective

1.2 : Front

1.3 : Back

1.4 : Left

1.5 : Right

1.6 : Top

1.7 : Bottom

Fig. 1.1 is a perspective view of an ovenware, showing my new design; Fig. 1.2 is a front elevational view thereof; Fig. 1.3 is a rear elevational view thereof; Fig. 1.4 is a left side

(Continued)

elevational view thereof; Fig. 1.5 is a right side elevational view thereof; Fig. 1.6 is a top plan view thereof; Fig. 1.7 is a bottom plan view thereof.

1 Claim, 7 Drawing Sheets
